SWIVEL CLAMP FOR TUBES

John Ward Blakely, 4031 Mary Ellen,
North Hollywood, Calif. 91600

Filed Aug. 23, 1965, Ser. No. 86,678

Term of patent 14 years

(Cl. D54—1)

Fig. 3

FIGURE 1 is a perspective view of a swivel clamp for tubes, showing my new design;

FIGURE 2 is a side elevational view thereof, the other side constituting an inverted mirror image of FIGURE 2; and

FIGURE 3 is an end elevational view.

I claim:

The ornamental design for a swivel clamp for tubes, substantially as shown and described.
